UNITED STATES PATENT OFFICE

GEDOR W. ALDEEN, OF ROCKFORD, ILLINOIS.

KEY GUIDE FOR LOCKS.

Continuation of application Serial No. 23,496, filed April 23, 1915. This application filed June 6, 1921.
Serial No. 475,560.

To all whom it may concern:

Be it known that I, GEDOR W. ALDEEN, a citizen of the United States, residing at Rockford, in the county of Winnebago and 5 State of Illinois, have invented certain new and useful Improvements in Key Guides for Locks, of which the following is a specification.

This invention relates in general to locks, 10 more particularly to the type commonly known as desk or cabinet locks, and has special reference to the key-guide and the manner in which it is secured in position. The present application is a continuation of my 15 application, Serial No. 23,496, filed April 23, 1915.

In locks of this general character as heretofore manufactured, the key-guide which is customarily in the form of a cylinder, has 20 been attached to or detachably connected with the lock case. Such constructions necessitated expensive and more or less complicated mechanism for locking the key guide or cylinder to the case for the purpose of 25 maintaining the guide in position. Furthermore, the mortise or opening in which the lock case is set and the opening communicating therewith into which the key-guide projects, must be accurately proportioned and properly positioned with respect to each 30 other in order to dispose the case and key-cylinder in proper relation to be locked together and to dispose the case in proper relation to the top of the drawer or other 35 part in which the lock is supported. It also follows that in locks of this general character, the lock case and key-guide are structurally dependent, so that one cannot be removed without necessitating removal of the 40 other.

It is desirable to remove the lock case independently of the key-guide, and one of the chief objects of the present invention is to provide a desk or cabinet lock in which 45 the key-guide will be structurally independent of the lock case and will be held in position in cooperative relation to the case by means independent of the lock case. By reason of such an arrangement both the lock 50 case and key-guide may be independently mounted or secured in operative position and the lock may be removed at any time independently of and without disturbing the key-guide. Furthermore, the cost of both 55 producing and installing a lock of this kind

is less than with prior known constructions, by reason of the fact that it comprises fewer parts and does not require a fine degree of accuracy to secure the lock and key-guide in proper operative relation.

Another important phase of my invention is in producing a lock of this type at a comparatively low cost. In this particular field, there are two distinct classes of desk or cabinet locks, commonly known as barrel-key 60 and flat-key locks. The barrel-key locks, so called by reason of the barrel shaped key, which is guided by a pin in the lock case itself, are generally recognized in the trade as an inferior and cheaper lock due to structural characteristics. The flat key-locks 65 so called because of the flat key employed, invariably comprises more parts and are more costly. These flat key locks are regarded in the trade as superior to the barrel-key locks 70 and are invariably applied to the higher and more costly grades of furniture. One of the characteristics of a flat key lock is its rotatable key guide, which appears at the face of the drawer or other lock-supporting 75 part. As mentioned above, however, this key-guide or cylinder is either permanently or detachably connected to and consequently structurally dependent upon the lock case, thereby giving rise to the objectionable features 80 already mentioned. Another object, therefore, of the present invention is to provide a flat key type of lock which may be produced and installed at practically the same or less cost than the barrel key type of 85 lock and which will have all of the advantages of and equal appearance to the flat key type of locks previously used, plus the advantages following from the structurally independent key guide and lock case.

Another object of my invention is to provide a key guide which will be simple in construction and cheap to manufacture and which can be quickly and easily secured in position regardless of the dimension between 90 the front of the lock case and the face of the part in which the lock is set, and irrespective of the accurate formation and relative position of the lock mortise or opening and the key guide opening.

Other objects and many of the attendant advantages of this invention will be readily apparent to those skilled in the art as the same becomes better understood by reference to the following description when consid- 105 110

ered in connection with the accompanying drawing, in which—

Figure 1 is a sectional view of a lock embodying my invention taken on the line 1—1

5 of Fig. 2;

Fig. 2, is a front elevation of the lock shown in Fig. 1;

Fig. 3, a sectional view on the line 3—3 of Fig. 4, showing a modified form of key

10 guide; and

Fig. 4, a face view of the construction shown in Fig. 3.

On the drawing, reference character 8 designates the front wall of a desk drawer in 15 which my improved lock is set. It should be understood, however, that a desk drawer front is shown for illustrative purposes merely and that my improved lock is capable of application to any part or article where 20 such a lock is desired. The wall 8 is provided with the usual mortise 9 to receive the lock case 11, which is set therein and held in position by a face plate 12 in the usual manner, and provided also with an opening 13 25 to receive the key guide. The lock proper arranged within the case 11 may be of any construction, and at present comprises the usual bolt 14 and other mechanism for operating and holding the same, which may be 30 of any well known or preferred construction. It should be understood that my invention contemplates the forming of any suitable mortise or opening for the reception of the lock case, and may be secured in such opening 35 by any suitable means, and further contemplates the forming of a suitable opening 13 in alignment with the key opening in the lock and intersecting the lock-receiving opening.

40 The key guide in this instance is shown in the form of a sheet metal cylinder 15 provided at its outer end with a radial flange 16 over which a sheet metal disk 17 is disposed and rotatably held in position by an inward- 45 ly projecting flange 18 loosely embracing the flange 16. The disk 17 is provided with the usual slot 19 through which the key is inserted into the lock.

The key guide instead of being attached to 50 or directly connected with the case 11, as has been customary heretofore, is simply set into the opening 13 in which it fits rather snugly and is then securely fastened in position by a plurality of radial projections 21 55 formed after the guide is placed in position by forcing the metal of the walls outwardly, as shown in Fig. 1. The spurs or projections 21 thus formed extend into the surrounding wood and securely hold the guide against 60 displacement.

In Figs. 3 and 4, I have shown a slightly different form of key-cylinder 29 in which the outer end is shaped to provide an inwardly disposed flange 31 overlying and holding in position a slotted disk 32 form-

ing the outer end of the cylinder. The retaining projections or spurs 21 are struck up in the same manner as those shown in Figs. 1 and 2.

From the foregoing, it will be observed 70 that I have provided a rotatable key-slot key-guide structurally independent of the lock case. It follows that the lock and key-guide may be secured in proper operative relation in any drawer or lock-supporting 75 part regardless of the dimension between the face of the lock and the face of the drawer or such part; that the bolt end of the lock case may always be set flush with the top of the drawer or lock-supporting part regardless of absolute alignment of the hole 13 with respect to the key opening in the lock, this being due to the structural independence of the lock case and key-guide and the allowance between said guide and case for the 80 key to properly accommodate itself to the lock; that the lock case may be removed at any time without disturbing, and entirely independent of, the key guide; that the key-guide by reason of its flanged outer end 85 structure constitutes an escutcheon trimming the hole in which the guide sets; and that the key-guide is not merely an escutcheon but an essential part of the lock in that it serves in itself to properly guide and hold the flat 90 key in operative relation to the lock for operating the latter. In regard to the flanged structure referred to, it should be noted that I do not consider this essential 95 to my invention in its broadest sense, but I 100 do consider it as a preferred form of construction, as it produces an escutcheon effect. Furthermore, in the particular example shown for purpose of illustration, the flanged structure constitutes a marginal 105 abutment which limits insertion of the tubular member into the hole 13 and thereby properly defines and limits the position of the key guide.

Attention is now directed to the manner 110 in which the key guide is secured in the body 8. As mentioned above, projections 21 are formed by pressing the metal of the walls of the tubular member outwardly after said member is placed in position. In other 115 words, the tubular member is unperforated before being inserted into the hole 13 and the spurs are struck or forced out of the unperforated wall of the tubular member. This or the equivalent may be done by inserting any suitable tool through the slot 19 and manipulating such tool to cause sharpened edges thereof to perforate the tubular member and press the perforated edges outwardly, thereby forming spurs and embedding them in the wood. This operation may 120 be performed by any suitable tool and at present is done by one (not shown) having pivotally connected jaws provided with oppositely disposed sharpened projections or 125 130

punches, when the handles of the jaws are compressed are forced apart to form and embed the spurs. It should be understood, however, that the present invention is in no way limited to the use of this or any other tool for applying the key guide; but that my invention contemplates broadly the provision of any suitable means for supporting the rotatable key-slot key-guide member on the body 8 independently of the lock case. It should also be understood that a key-guide as claimed hereinafter may be formed of any suitable material.

It is believed that the foregoing conveys a clear understanding of the objects prefaced above, and while I have illustrated but practically a single embodiment of my invention, it should be understood that considerable change might be made in details of construction and arrangement of parts without departing from the spirit and scope of the invention as expressed in the appended claims.

I claim:

1. A key-guide, comprising a tubular member adapted to be inserted in an opening formed in the part receiving the lock case with which the key-guide cooperates but structurally independent thereof, said member being supported by and secured within the wall of said opening and having a flange at its outer end, and a key-slot disk rotatably supported upon said flange, the flange and disk structure forming a marginal abutment limiting insertion of the tubular member into said opening and trimming the same as an escutcheon.

2. A key-guide, comprising a tubular member adapted to be inserted in an opening formed in the part receiving the lock

case with which the key-guide cooperates but structurally independent thereof, said member having a flange at its outer end, and a key-slot disk rotatably supported upon said flange, said member having outstanding securing elements pressed outwardly from said member into the walls of said opening. 45

3. The combination with a wooden supporting member having a lock case opening and a key-guide opening, of a key-guide 50 structurally independent of the lock case and adapted to be inserted in the second mentioned opening, comprising a tubular member equipped at its outer end portion with a rotatable key-slot disk and having, at 55 its inner end portion, spurs struck out from the unperforated body of said member and embedded in the body of the wooden supporting member.

4. The combination of a key-guide comprising a tubular member adapted to be inserted in an opening formed in the part receiving the lock case with which the key-guide co-operates but structurally independent thereof, a key-slot disk rotatably supported on the outer end of said tubular member at the face of said part, and means operating directly between said tubular member and the wall embracing it, for securing said member in fixed operative position in 60 65 said part.

5. A key guide for a lock comprising a tubular member structurally independent of the lock, adapted to be inserted in an opening in the lock support, said member being 70 75 retained against displacement from said support by the surrounding wall of said opening, and a key-receiving slot disk rotatably secured to the outer end of said member.

GEDOR W. ALDEEN.

Certificate of Correction.

It is hereby certified that Letters Patent No. 1,437,878, granted December 5, 1922, upon the application of Gedor W. Aldeen, of Rockford, Illinois, for an improvement in "Key Guides for Locks," were erroneously issued to the inventor, said Aldeen, whereas said Letters Patent should have been issued to *National Lock Co., of Rockford, Illinois, a Corporation of Illinois*, said corporation being assignee of the entire interest in said invention, as shown by the records of assignments in this office; and that the said Letters Patent should be read with this correction therein that the same may conform to the record of the case in the Patent Office.

Signed and sealed this 9th day of January, A. D., 1923.

[SEAL.]

KARL FENNING,

Acting Commissioner of Patents.
